UNITED STATES PATENT OFFICE.

ALVAH C. ROEBUCK AND ADOLPH J. PRUSZYNSKI, OF WOODSTOCK, ILLINOIS, ASSIGNEES TO WOODSTOCK TYPEWRITER COMPANY, OF WOODSTOCK, ILLINOIS, A CORPORATION OF ILLINOIS.

PAPER-EDGE GUIDE.

1,217,638.

Specification of Letters Patent. Patented Feb. 27, 1917.

Application filed August 30, 1915. Serial No. 47,915.

To all whom it may concern:

Be it known that we, ALVAH C. ROEBUCK and ADOLPH J. PRUSZYNSKI, citizens of the United States, residing at Woodstock, in the county of McHenry and State of Illinois, have invented certain new and useful Improvements in Paper-Edge Guides, of which the following is a specification.

This invention relates to typewriters, and more particularly to that portion of the paper feeding mechanism of a typewriter by means of which the edge of the paper is guided during its feeding movement in positioning the paper and as it is fed to the printing mechanism.

The principal object of the invention is to provide an improved construction, combination and arrangement of parts for accomplishing the result above mentioned. Other objects will appear hereinafter.

In the drawings—Figure 1 is a view in elevation of a paper edge guide constructed in accordance with the principles of our invention and applied to the paper table of a typewriter; Fig. 2 is a view in elevation of the rear of a paper table to which the guide is connected; Fig. 3 is a sectional view on the line 3—3 of Fig. 2; and Fig. 4 is a perspective view of a supporting bracket.

In order to facilitate the proper feeding of paper or other material to the platen of a typewriter, it is convenient to have a guide, usually at the left-hand side of the paper table, against which the left-hand edge of the paper is pressed, for quickly and accurately placing paper to provide a predetermined margin, and to assist in alining the paper so it will be straight upon the platen. By making the paper edge guide adjustable, margins of various widths may be made, and the typewriter is more readily adaptable for use in writing forms and the like where a number of sheets of the same size are to be inserted one after the other.

In the accompanying drawing, the reference numeral 5 designates generally a paper table to which this paper edge guide may be applied. It is usually mounted in end plates 6 of a typewriter carriage or movable sub-carriage in which is a rotatable platen 7, a cross-bar 8 usually connecting the end plates 6 and forming a rest against which the paper table is moved. In its preferred construction, the paper table is formed with

ears 9 at the ends, by means of which it is pivoted in the end plates.

Secured to the paper table at the rear thereof, is a bracket 10 having bent extremities 11 in each of which is a recessed slot 12. This bracket may be secured to the table by rivets 13 or other suitable fastening devices. The guide proper consists of an arm 14 slidable in the slots 12 of the bracket member 10 and preferably formed with a central longitudinally extending groove 15 pressed in the material on one side forming a strengthening rib on the other side. At one end, this arm is provided with a stop 16 preferably consisting of a nut and screw secured thereto, and at the other end it is formed with a bent portion 17 extending over the upper side of the paper table 5 and down over the front or upper face thereof. The left-hand edge of the portion that is bent over the front of the paper table, is turned upwardly at right angles to form an abutment 18 which extends transversely across the paper table and at right angles to the axis of the platen, so that when the left-hand edge of a sheet of paper is pressed against the upstanding edge of the guide the paper will be fed in proper alinement to the platen.

In order to hold the paper edge guide firmly but yieldingly in any position at which it is placed, a spring 19 is pressed in the bracket and bears against the arm 14 of the guide, tending to hold it firmly in place in the slots 12. This spring is preferably formed with the extremities rounded outwardly from the central portion and with projections 20 formed in the extremities which are adapted to engage in the groove 15 of the member 14, so that the extremities of the spring bear against the member 14 while the center bears against the bracket 10, the projections 20 serving to hold the paper edge guide in position and preventing the spring from disengagement therewith. Of course by pressing down the ends of the spring it can be easily removed from the bracket 10 and by removing the stop 16 the guide may be inserted or removed from the slots in the bracket.

We claim:

1. A paper edge guide comprising a slotted guide, a member slidable therein having a bent portion at one end to prevent it sliding from the support, and a removable

stop at the other end to prevent the member sliding from the support, and a spring to hold the member yieldingly in place.

2. A paper edge guide comprising a paper table, a bracket secured to the table and ends bent therefrom with recessed slots therein, and a member having an arm slidable in the slots with an extension thereof bent over the top of the table to the opposite side thereof.

10 3. A paper edge guide comprising a member with a portion adapted to engage the edge of paper and an arm extending therefrom having a strengthening rib extending longitudinally thereof, and a single support 15 with opposite ends formed with recessed slots in which the said arm is slidable.

4. A paper edge guide comprising a paper table, a support at the rear thereof having outstanding parts with recessed slots therein

20 in alignment longitudinally of the table, a member having an arm slidable in the said slots with a guide portion extending over the edge of the table to the opposite face thereof, and a spring tending to press the member outwardly in the slots to hold it yieldingly in place and to hold the portion on the opposite side of the table adjacent the face thereof.

25 5. A paper edge guide comprising a paper table, a support at the rear thereof comprising projecting slotted portions, a member having an arm with a groove slidable in the said slots with a paper guiding portion ex-

tending to the opposite side of the table, and a spring disposed between the paper table 35 and the arm having projections to engage in the groove of the said arm for holding the arm in place.

6. A paper edge guide comprising a paper table, a bracket secured to the rear thereof 40 having extremities bent away from the table with a slotted recess in each extremity, a member having an arm slidable in the said slots, another arm extending over the upper edge of the paper table and with an angular 45 portion one side of which lies parallel with the front face of the paper table and the other side of which stands out at right angles thereto forming an abutment for the edge of the paper, and means to yieldably 50 hold the said member in any adjusted position to which it may be slid.

7. The combination with a paper table, of a supporting bracket secured to the rear thereof having spaced parts with recessed 55 slots, a paper edge guide having an arm slid- able in the slots and a guide portion ex- tending over the top edge of the paper table, and a spring interposed between the arm and the bracket, and between said slotted parts 60 to hold the guide yieldingly in any position.

In testimony whereof we have signed our names to this specification, on this 27th day of August, A. D. 1915.

ALVAH C. ROEBUCK.

ADOLPH J. PRUSZYNSKI.
